UNITED STATES PATENT OFFICE.

PETER O. DE MOSS, OF MORO, OREGON.

DESIGN FOR A MEMBER FOR SACK-SUPPORTS.

SPECIFICATION forming part of Design No. 35,680, dated February 4, 1902.

Application filed July 6, 1901. Serial No. 67,368. Term of patent 7 years.

To all whom it may concern:

Be it known that I, PETER O. DE MOSS, a citizen of the United States, residing at Moro, in the county of Sherman and State of Oregon, have invented and produced a new and useful Design for a Member of a Sack-Support, of which the following is a specification, reference being had to the accompanying drawings.

This invention relates to a design for a sack-support; and the essential features reside in the design as illustrated in the accompanying drawings, wherein—

Figure 1 is a perspective view of the support embodying the features of the design. Fig. 2 is a rear elevation of the same.

The design is characterized by a cylindrical tubular element 1, having an offset 2, with concave faces 3 intersecting a vertical face 4, the said offset having a vertical slot 5. At a diametrically opposite point and in the center the element 1 has curved projections 6 and 7, the projections 7 extending outwardly from

the projection 6, and connecting with the projection 7 is a circularly-arranged rod 8, which is horizontally disposed and has outer reduced points 9. Within the circularly-arranged rod and nearer the element 1 is a vertically-disposed concavo-convex member 10, with upper and lower curved edges 11, a portion of the member projecting below the plane of the rod 8 and the concave face thereof disposed inwardly. The upper and lower curved edges continue into two vertical straight edges 12.

Having thus fully described the invention, what is claimed as new is—

The design for a member of a sack-support, as herein shown and described.

In testimony whereof I affix my signature in presence of two witnesses.

PETER O. DE MOSS.
